UNITED STATES PATENT OFFICE.

FRANK FRUCTUOSO MARTIN, OF GLOUCESTER, MASSACHUSETTS.

MEANS FOR REEFING SAILS.

SPECIFICATION forming part of Letters Patent No. 373,671, dated November 22, 1887.

Application filed July 26, 1887. Serial No. 245,367. (No model.)

To all whom it may concern:

Be it known that I, FRANK FRUCTUOSO MARTIN, a citizen of the United States, residing at Gloucester, in the county of Essex and State 5 of Massachusetts, have invented certain new and useful Improvements in Means for Taking a Reef in Sails; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 This invention relates to devices for reefing sails, and has for its object to devise a simple construction and arrangement of reef-tackle and reef-eyelets whereby the ends of the reef-loops may extend on one side of the sail above 20 the foot thereof, so that in reefing the strain will come on one side of the sail, thereby facilitating the operation of reefing and preventing the foot of the sail being cut by the reef-loops, which usually pass about it.

25 The improvement further consists in the novel features of construction of parts, herein-after more fully described, claimed, and shown in the annexed drawings, in which—

Figure 1 is a side view of a sail boat or yacht, 30 parts being broken away, showing the application of my invention; and Fig. 2, a detail perspective view of a portion of the sail, showing a reef-loop and the manner of connecting it with the main reef-line.

35 The boat A is provided with the mast B, bowsprit C, mainsail D, and halyard E, of old and well-known construction. The sail at a suitable distance above its foot is provided with a series of reef-eyelets, F, and below each 40 of said eyelets, close to the foot of the sail, is arranged a group of three eyelets. Two eyelets, e e' , of each group are in line with the corresponding eyelet F, and the third eyelet, e^2 , is arranged to one side of a straight line passing through the two eyelets e and e' and opposite the space between them. The reef-loops 45 G pass through the reef-eyelets F and extend down on each side of the sail. The end of the

loop on one side of the sail passes through the eyelet e^2 to the opposite side of the sail, and the other end of the loop passes through eyelet e and back to the same side of the sail through eyelet e' . By this arrangement all the ends of the reef-loop are on the same side of the sail and connect with the main reef-line H a little 55 above the foot of the sail.

The sail is reefed, in the usual manner, by hauling in on the reef-line, and is unreefed by drawing down on the halyard E.

Having thus described my invention, what 60 I claim, and desire to secure by Letters Patent, is—

1. The combination, with the sail having a series of reef-eyelets above the foot of the sail at desired distances, and eyelets in corresponding groups of three arranged near the foot of the sail, of the reef-loops passed through the upper set of eyelets and having one end of each loop passed through one of the eyelets of the corresponding group of eyelets, and having the 70 other end of the loops passed back and forth through the remaining two eyelets of said groups, and the reef-line connecting the free ends of the reef-loops on one side of the sail, substantially as set forth. 75

2. The combination, with the sail having a set of eyelets at a distance above its foot and corresponding groups of three eyelets arranged, as shown, close to its foot, of the reef-loops passed through the upper eyelets and 80 having one end of the loops passed through one eyelet of each of said groups and the other end of the loop passed back and forth through the remaining two eyelets of each group to the same side of the sail from which it first departed, and the main reef-line having the ends of the reef-loop connected therewith on the same side of and above the foot of the said sail, substantially as and for the purpose specified. 85

In testimony whereof I affix my signature in 90 presence of two witnesses.

FRANK FRUCTUOSO MARTIN.

Witnesses:

FRANK N. HODGKINS,
WM. P. DOLLIVER.
